Primary Examiner — Calvin E Vansant

(74) Attorney, Agent, or Firm — James L. Young;
Westman, Champlin & Koehler P.A.(57) **CLAIM**

The ornamental design for a paint grid, as shown and described.

DESCRIPTION

FIG. 1 is a perspective view of a first embodiment thereof;

FIG. 2 is a rear view thereof;

FIG. 3 is a front view thereof;

FIG. 4 is a bottom view thereof;

FIG. 5 is a top view thereof;

FIG. 6 is a right side view thereof, as taken from the right side of FIG. 3;

FIG. 7 is a left side view thereof, as taken from the left side of FIG. 3; and,

FIG. 8 is a sectional view, as taken along lines 8-8 in FIG. 3.

The broken lines depict portions of the paint grid that form no part of the claim.

1 Claim, 5 Drawing Sheets(56)
